[57] CLAIM

The ornamental design for a stationery case and calculator, as shown and described.

DESCRIPTION

FIG. 1 is the perspective view of a stationery case and calculator showing my new design;

FIG. 2 is the front elevational view thereof;

FIG. 3 is the rear elevational view thereof;

FIG. 4 is the left side elevational view thereof;

FIG. 5 is the right side elevational view thereof;

FIG. 6 is the top plan view thereof;

FIG. 7 is the bottom plan view thereof;

FIG. 8 is the perspective view thereof, with the cover shown open;

FIG. 9 is the perspective view showing an alternate position; and,

FIG. 10 is a perspective view of a second embodiment, with the front, rear, left side, right side and bottom view being identical to FIGS. 2-5 and 7.
